UNITED STATES PATENT OFFICE.

JOHN REID, OF NEW YORK, N. Y.

FURNACE-FRONT BAFFLE CONSTRUCTION.

1,350,468.

Specification of Letters Patent. Patented Aug. 24, 1920.

Application filed March 3, 1919. Serial No. 280,410.

To all whom it may concern:

Be it known that I, JOHN REID, a subject of the King of Great Britain, and residing at 30 Church street, in the city of New York, 5 in the State of New York, in the United States of America, have invented a new and useful Furnace-Front Baffle Construction, of which the following is the specification.

The invention relates to improvements in 10 furnace front baffle construction, as described in the present specification and illustrated in the accompanying drawings, that form part of the same.

The invention consists essentially of the 15 novel construction and arrangement of the baffles on the fire box side of the front.

The objects of the invention are to eliminate, as far as possible, the destruction of the back plate through the failure of the 20 baffles to accomplish their purpose; to furnish a refractory member that will not readily scale; to avoid accidents at sea due to the delays from injuries incident to the sudden overheating of exposed plates in furnace fronts; to insure regularity in the generation of steam; to efficiently complete the 25 structures described in my Patents 1,297,247 dated March 11, 1919, and 1,318,331 dated October 7, 1919; to provide in a furnace 30 front a baffle assembly and construction that will effectively resist the heat and that will endure for a comparatively long period.

In the drawings, Figure 1 is an elevation of the back plate on the fire box side, showing 35 the baffles in their preferred positions.

Fig. 2 is an enlarged detail of the upper central baffle.

Fig. 3 is a cross sectional view through the said upper baffle.

Fig. 4 is an enlarged bottom plan view of the baffle forming a yoke between the side or wing baffles.

Fig. 5 is an enlarged sectional view of the yoke piece.

Fig. 6 is a cross sectional view of the upper baffle, showing the grid riveted to the base plate of the baffle.

Fig. 7 is an enlarged detail of a baffle showing another means employed for holding 50 the refractory coating.

Fig. 8 is a detail view in vertical section, showing the relations between the front plate, the back plate, the tenon and one of the filleted upper corners.

Like numerals of reference indicate corresponding parts in each figure.

Referring to the drawings, the numeral 1 indicates the upper baffle covering the exposed surface of the back plate 2 from side to side and from the top down to the fuel 60 passage 3.

The side or wing baffles 4 and 5 cover the exposed surface of the back plate 2 from the baffle 1 down to the fire box level, as indicated by the structural supports 6 and 7. 65

The yoke baffle 8, which is located beneath the central portion of the upper baffle 1 and between the upper portions of the side baffles 4 and 5, covers the back plate at the inner end of the fuel passage. The baffle 1 has 70 a straight lower edge and the baffles 4 and 5 have straight inner vertical side edges. The yoke baffle 8 conforms to the configuration of the space defined by the adjacent edges of the baffles 1, 4 and 5. The inner side 75 faces of the sides of the yoke baffle 8 are curved and the sides terminate in the tenoned ends 10 meeting at each side the tenon shoulders of the plates 11 and 12 secured to the side baffles 4 and 5, said yoke baffle being 80 bolted to the baffle 1.

It will now be seen that the back plate of the furnace front within the fire box and forming the front wall thereof is covered by a particular arrangement of baffle plates, 85 which are constructed in a special manner as set forth in detail hereinafter.

The door baffle 13 is arranged in its customary position and with the baffles 1, 4, 5 and 8 completes the protective covering for 90 the otherwise exposed surface of the back plate 2 and the door.

Each baffle in the arrangement described is made with a base plate 14, having a considerable number of suitably spaced holes. 95

The baffles are provided with grids and the grid 16 in one form is shown with the square meshes 17 and the crossed bars 18 preferably inwardly flanged at 19 to form pockets of said squares, the latter being 100 formed to register with the arrangement of holes 15, so that each square will have a central hole leading therefrom through the base plate 14. The grid 16 is secured to a base plate 14 by the bolts 20 and nuts 21, 105 though it may be secured by rivets or in the casting process.

The squares or pockets 17 are filled with a

refractory and plastic substance 22 such as asbestos cement and in this filling a central hole 23 is made, which corresponds and registers with the holes 15 and the whole may be surrounded by an outer wall 24.

As before explained, the side baffles 4 and 5 are formed and placed to receive the baffles 11 and 12 to meet the yoke 8, and the latter contains the grid surface construction on the under side, so far as it can be applied thereto.

The baffle construction thus described applies particularly to that class of furnace fronts for structures known in practice as the "Scotch" type of forced draft furnaces and it is particularly suitable for the back plate of said type of front, as the upper plate and side or wing plates are joined by the yoke plate and these with the door plate cover all surfaces, which would otherwise be exposed.

The specific construction of the grid and refractory pockets is very important though other means for anchoring refractory material has been known heretofore. This invention is concerned largely in practical methods to standardize furnace fronts, in order to effect economy and despatch in production and with this in view, a cast base plate is provided with a grid which with the base plate forms pockets of any suitable shape and here shown as square and this grid is preferably fixed to the base plate in such a way as to be removable therefrom, thereby furnishing a means of readily renewing the refractory substance, though it is likely to last for a considerable period and also to stand a great heat, in view of the area of each mass being so confined as to leave a comparatively small exposed surface in each pocket, thereby lessening the liability to cracks or other injury. It is quite important to insulate the base plate from the grid and to do this a thin asbestos mat 30 is introduced between base plate and grid so that the heat is not conducted directly from the grid to the base plate thereby avoiding warping and cracking and making it practical to have a comparatively thin base plate. This mat also forms a splendid additional anchor for the refractory paste. This is especially important where there may be a small space of the mat not covered by the grid.

The grid may be made of strips bolted together as shown in Fig. 8 and in this form of the invention the flexible strips 25 are drawn together and secured by the bolts 26, rivets or other means of fastening, thereby forming the pockets 27.

It will thus be seen that the cast grid or the malleable or machined grid may be used with approximately equal efficiency, though for cheapness and effectiveness, it will be difficult to equal the cast grid bolted to the base plate, as that facilitates both the in-

stallation and repairs in furnace fronts and there is a certain rigidity about the cast metal, that combines well with the refractory nature of the fibrous cement, the two presenting a solid front almost impregnable in resisting the gases.

The yoke feature of this invention is of great service, so far as durability is concerned, for the corners and edges of the back plate at the fuel passage are almost universally neglected and consequently burnt out first, which destroys the whole front in solid cast fronts, but the new arrangement of baffles overcomes this difficulty and no part of the back plate within the fire box is left without protection.

Various changes may be made in the construction and some in the arrangement for different types of front, so long as they are within the scope of the claims for novelty following.

What I claim is:—

1. In furnace front baffle construction, a back plate forming the inner front wall of the fire box and having a fuel opening, a plurality of baffles partially covering said walls and situated on the back plate of the furnace front above and on either side of the fuel passage opening and a yoke piece bridging the distance across said fuel opening at the upper end thereof and covering the portion of said wall left uncovered by the aforesaid baffles.

2. In furnace front construction, a back plate forming the inner front wall of the fire box and having a fuel opening, an upper baffle secured to said plate above the fuel opening, side or wing baffles below said upper baffle and a yoke baffle secured to said upper baffle and filling in the corners formed by said side baffles and said upper baffle, said baffles forming a refractory covering for said front wall.

3. In furnace front baffle construction, a back plate forming the inner front wall of the fire box and having a fuel opening, an upper baffle secured to said back plate above the fuel opening, a pair of side or wing baffles extending downwardly from said upper baffle, one on each side of the fuel opening, filling side plates secured to said wing plates and having tenon shoulders, a yoke piece extending across the upper end of the fuel opening and filling in the corners formed by said upper and side baffles and having tenon ends meeting the aforesaid tenon shoulders, said baffles forming a refractory covering for said inner front wall, and a door baffle completing the baffle equipment.

4. In furnace front baffle construction, a base plate having holes therethrough, a grid in mesh form rigidly secured to said base plate, and forming pockets with the same, and refractory substance in said pockets

- having holes therethrough registering with the aforesaid holes.
5. In furnace front baffle construction, a base having a plurality of holes, a grid in crossed bar form secured to said base having flanges forming retaining lips, and refractory material filling said grid and having holes therethrough corresponding to and aligning with the aforesaid holes.
- 10 6. In furnace front baffle construction, a base plate having a plurality of holes, a refractory substance holder rigidly secured to said base plate and formed with a plurality of adjoining apertures suitably shaped to retain the substance, a plastic substance of a refractory nature and filling said apertures having holes therethrough registering with the aforesaid holes, and fastening members for securing said holder to said base plate.
- 15 7. A furnace baffle construction comprising a supporting plate, having openings there-
- through, a member provided with openings secured to said plate and masses formed from fibrous refractory plastic material in the openings in said member, said member and masses being provided with openings registering with the openings of the supporting plate. 25
8. In furnace front baffle construction, a base plate forming a grid support, an asbestos mat mounted on said base and correspondingly shaped to said base plate and forming the means of separating the base from the grid, a grid mounted on said mat and adapted to receive a plastic substance, fasteners securing said grid to said base 30 plate and refractory plastic substance in said grid. 35

Signed at the city of New York this 13th day of Feb., 1919.

JOHN REID.
